UNITED STATES PATENT OFFICE.

NELLA B. STRAWN, OF ANTONITO, COLORADO.

WASHING MACHINE.

Application filed December 9, 1926. Serial No. 153,628.

This invention relates to improvements in washing machines and more particularly to an improvement in that type of washing machine employing a corrugated roller as a means for scrubbing the cloths which are being washed.

An important object of the invention is to provide means operating in combination with such a roller to feed a cloth to the roller for treatment thereby, which will maintain the cloth spread, so that the roller will have action over the entire face thereof and which will permit operation of the roller by a continuous rotary motion instead of the oscillating motion now commonly employed in such devices.

A further object of the invention is to produce an attachment for such washing machines whereby these objects are accomplished.

A more specific object of the invention is to produce a belt for use with such washing machines having means thereon for engaging and holding the cloths which are to be washed whereby they will be fed beneath the face of the roller by a continuous rotary motion thereof.

These and other objects I attain by the construction shown in the accompanying drawings, wherein for the purpose of illustration is shown a preferred embodiment of my invention and wherein:

Figure 1 is a front elevation of a washing machine embodying a belt constructed in accordance with my invention;

Figure 2 is a vertical sectional view therethrough, the machine being indicated in position in the tub shown in section lines;

Figure 3 is a section on the line 3—3 of Figure 1;

Figure 4 is an enlarged fragmentary front elevation partially broken away to show the manner of attaching the supporting rods.

Referring now more particularly to the drawings, the numeral 10 generally designates a corrugated roller of a washing machine of this character. In the type of machine illustrated, this corrugated roller is urged resiliently downwardly toward a bed 11 consisting of a plurality of rollers. The corrugations of the roller act upon a cloth placed therebeneath to knead the same much after the manner in which said cloths are manipulated in hand washing. With the ordinary structure of this type of machine,

the shaft 12 upon which the roller 10 is mounted is rocked after the cloth has been placed in position beneath the roller. When it is deemed that the cloth has been sufficiently treated, it is discharged from beneath the roller by continuing the rotation to a point where the roller forces the cloth from the bed 11.

In accordance with my invention, I provide a belt comprising a double canvas strip 13, the ends of which are provided with coacting fasteners 14 whereby the strip may be connected to form a band. Extending transversely of one face of this strip are bars 15, the ends of which are provided with eyes 16 which are stitched to the strip adjacent the side edges thereof. The edges of the strip have applied thereto a bead, generally designated at 17, this bead having its opposite side faces projecting laterally of the inner and outer faces of the strip. The bead preferably consists of an outer covering of rubber or rubberized material 18 applied to a circular padding core of worsted or other soft material, indicated at 19, the rubber or rubberized material indicated at 18 being connected together at one side of the bead in such manner as to form a stem 20 which may be secured to the longitudinal edges of the cloth and which serves to cover and protect against contact with the roller 10 the stitching attaching the ends of the bars 15 to the strip.

In the use of the device, one end of the strip is inserted between the roller 10 and bed 11 and the roller 10 rotated until the end of the strip projects from the opposite edge of the bed when the opposite end of the strip is connected thereto by the fasteners 14. The cloths which are to be washed are then placed between the bars 15 and the adjacent face of the band and the shaft 12 continuously rotated in one direction. During this operation, the bead with its rubber face contacting the rollers 10 and 11, provides a positive drive for the belt, even during the passage of cloths beneath the roller. This type of washer is usually employed upon an open tub T containing water and the cloths which are to be washed and the lower end of the band will extend into the water. Therefore, during rotation, the cloths will be successively passed between the roller 10 and bed 11 and through the water within the tub until they have been sufficiently treated.

Such a device may be either operated by a hand crank or from any suitable source of motive power.

Since the construction hereinbefore set forth is capable of a certain range of change and modification without materially departing from the spirit of the invention, I do not limit myself to such specific structure except as hereinafter claimed.

10 I claim:—

An attachment for washing machines of the character described comprising a strip of material having near its opposite end edges coacting fasteners whereby said end edges may be connected to form an endless

band of the strip, holding elements extending transversely of the band on one face thereof and bearing elements extending longitudinally of the side edges of the band, said holding elements each comprising a bar having 20 means securing its ends to the strip adjacent the side edges thereof, said bearing elements each comprising a compressible bead and an attaching stem therefor, the attaching stems of the beads extending over the 25 securing elements of the bars and connected to said strip.

In testimony whereof I hereunto affix my signature.

NELLA B. STRAWN.
